UNITED STATES PATENT OFFICE.

THOMAS CARNEY, OF ST. PAUL, MINNESOTA.

SELF-REGISTERING CASH-BOX.

SPECIFICATION forming part of Letters Patent No. 334,347, dated January 12, 1886.

Application filed August 3, 1885. Serial No. 173,420. (No model.)

To all whom it may concern:

Be it known that I, THOMAS CARNEY, esquire, a subject of Her British Majesty Queen Victoria, residing at St. Paul, in the 5 county of Ramsey and State of Minnesota, have invented certain new and useful Improvements in Self-Registering Cash-Boxes; and I do declare the following to be a full, clear, and exact description of the invention, 10 such as will enable others skilled in the art to which it appertains to make and use the same, reference being had to the accompanying drawings, and to letters or figures of reference marked thereon, which form a part of this 15 specification.

Figure 1 of the drawings is a representation of my cash-box in perspective. Figs. 2 and 3 are perspective details. Fig. 4 is a vertical transverse section of the cash-box. Figs. 5 20 and 6 are detail views.

This invention relates to cash-boxes for making change in transacting business, its objects being to rapidly handle coin of different denominations without likelihood of error, and 25 to quickly ascertain how much of the different kinds of coin are at any time in the cash-box.

The invention consists in the construction and novel arrangement of parts hereinafter described, and pointed out in the appended 30 claims.

Referring to the accompanying drawings by letter, A designates the casing or box of the lower part of the machine, of general rectangular form, within the front portion of which 35 is secured the casting B. The upper horizontal plate of the said casting has made in it the slots b, running from front to rear of the machine, and having at their rear ends the rubber stops b'. Running downward and outward 40 from the top plate of the casting is an inclined plane, C, the sides of which are provided with supporting and coin-directing flanges, and which converge and end in the chute or spout c, which passes out of a slot in 45 the front of the casing. c' is a recess made in the said front below the chute, for the purpose of easily receiving in the hand the coin that falls from the chute.

The casing A is open above the casting B, 50 and has detachably secured above the latter a vertical casing, D, open in front. Within this casing is secured a casting, E, provided

with the coin tubes or boxes e, which are open in front and have their backs or walls concaved to fit the denomination of coin they are 55 to receive. The upper ends of the said tubes or boxes are open, their lower ends being closed by a casting, F, which is bolted to the lower end of the casting E and provided with slots f, which stand, respectively, above the 60 slots b in the casting B and below the coin-boxes. The open fronts of the coin tubes or boxes are closed by a metallic plate, G, the side edges of which slide in ways or grooves G', made in the front edges of the sides of the 65 casing D.

g are vertical slots made in the plate G and standing in front of the coin boxes or tubes, to view the contents thereof, and g' is a flange standing outward at right angles from the foot 7c of the plate and flush with the bottom of the coin-boxes when the plate G is pushed home.

The upper surface of the casting F is furnished with depressions F', which run partly within the coin tubes or boxes, have their rear 75 ends correspondingly concaved, and their floors inclining downward and outward. The depressions form exits for the coin below the flange g', their inclination aiding the escape of the same.

g² are transverse slots crossing the tops of the slots g below a flange, g³, at the top of the plate G, and lying in front of the coin tubes or boxes. By means of these slots g² coin may 85 be inserted in the boxes without lifting the lid g⁴, which is hinged at its rear edge to the rear upper corner of the casing D and has its front edge lying upon the flange g³ of the tubes. The casting E is so secured in the casing D that the coin tubes or boxes incline 90 slightly forward from top to bottom.

H is a transverse rod running through the casing A near the base of the same, below the coin tubes or boxes, and H' is a similar rod, slightly to the rear of and above the same. 95 The ends of these rods are supported in the side walls of the frame or casing A. Each coin-box has a corresponding lever, h, pivoted at its lower end upon the rod H, and has a slightly curved arm, h', extending forward 100 from it at a point above its pivot.

I is a key, the rod of which passes through a suitable directing-aperture in the casing A in front of the coin tubes or boxes, its lower

end being loosely pivoted to the end of the arm h' , as shown.

I' is a spring, the lower end of which is secured to the rod H by passing through an opening therein. The spring thence passes to the rod H', around which it coils, and, running thence upward, passes through a lug on the rear edge of the lever h. The action of the spring is to return the upper end of the lever h backward after it has been forced forward by depressing the key I. The upper end of the lever h has a head, h^4 , beveled downwardly from its center to its front, as shown. From the center of this head stands a lug, upon which is pivoted the pushing-head i, having a flat base. From the top of the head i stands a stem having a beveled upper end, i'. When the depression of the key I forces the lever h forward, the point of the bevel i' catches against the rear edge of the last coin in the coin-box, so that it is carried from out the pile of coin and forced down on the inclined plane C, whence it passes to the chute c and out of the machine. When the key is released, the under surface of the next coin in the pile turns forward the point of the bevel i', so that the latter passes under the coin without catching thereon, the head i being turned forward, with its base resting on the forward bevel on the head of the lever h. When said lever is fully back, the junction of its head h^4 and the head i strikes against the lug b', the bevel i' again becoming inclined. To drive the coin out of its box, the head i must pass through the adjacent slots b and f.

On the case above each key is marked upon a proper part of the casing A the number in cents or dollars of the coin contained in the box with which that key corresponds.

The rear portion of the casing A, behind the upright casing D, is formed into a chamber to receive a coin-drawer, J, formed of the casting J' and the pieces J², secured to the end thereof. The casting J' is formed into a number of banks of cells, preferably three, which rise, stair-like, above and break joints with each other. Oval slots j are formed in the casting on the front edge of each cell, for convenience in removing coin therefrom. When there are three banks of cells, the lowest ones are preferably to receive each ten silver dollars, the second ones each ten dollars in half-dollars, and the upper ones each five dollars in quarter-dollars.

Both the coin-drawer J and the casing D may have proper side handles for operating them.

The method of using the device is evident from the foregoing description.

The casing D and the coin tubes or boxes 60 containing the coin can be removed from the cash-box and locked up in a vault for safety.

Having described this invention, what I claim, and desire to secure by Letters Patent, is—

65

1. In a cash-box, the combination of a coin-tube, a key, a lever, and a pivoted head, the coin-tube having a slotted bottom, the lever connected with the key, and the head pivoted to the upper end of the lever and adapted to be moved in the slot of the tube, substantially as specified.

70

2. The combination, in a cash-box, of a coin-tube, a key, a pivoted spring-lever, and a head, the tube having a slotted bottom for the passage of the head, the key connected with the pivoted lever, which latter has its upper end beveled forwardly, the head also beveled forwardly on its under side and hinged to the said lever, whereby the downward movement 80 of the key will carry the hinged head through the slot of the coin-tube and remove the lowest coin therefrom, substantially as specified.

75

3. The combination, with a coin-tube, of a pivoted lever, a hinged head, a finger-key, and 85 a chute, the horizontal portion of the chute being slotted beneath the coin tubes, the key connected with the pivoted lever, and the head hinged to the upper end of the said lever, whereby pressure upon the key will cause the 90 hinged head to move in the slots of the chute and carry the lowest coin in the tube out upon the chute, substantially as specified.

95

4. In a cash-box, the combination of the main casing A, the casting B, provided with the slots b, and having the inclined plane and chute formed upon it, the vertical casing D, the casting E, provided with the coin-tubes e, the casting F, provided with the slots f, the rods H H', the levers h, provided with the 100 arms h' and adapted to have their upper ends push the lower coin of any box out of the latter, the keys I, and the springs I', substantially as specified.

105

5. In a cash-box, the combination, with the 110 coin-tubes and the casting B, having the inclined plane and chute formed thereon and provided with the slots b and stops b', of the keys I, rods H H', levers h, provided with the arms h', springs I', and heads i, pivoted to the 115 upper ends of the levers h, as specified.

120

In testimony whereof I affix my signature in presence of two witnesses.

THOMAS CARNEY.
